11-1878. L. M. Samuel Hollister of San Francisco. Cal.

DES. 2438

Letters Patent No. 2438. Dated Sept. 3, 1878.

Print. in Design for a centre piece.

The schedule referred to in these Letters Patent and making part of the same.

To all whom it may concern:

Be it known that I, Samuel Hollister, of the City and County of San Francisco, State of California have originated and designed a new Centre Flower for buildings in alto relief, of which the following is a full, clear, and exact description, reference being had to the accompanying drawings making part of this Specification.

It is a photograph of a centre flower of my design composed of plaster of paris, so called, cast and modelled in the usual way well known to workers in stucco, with the exception, however, to cast the different portions in gelatin moulds, instead of plaster, as this manner of casting imparts a higher degree of relief to the design and brings out the figures with greater clearness.

My said Design consists of scroll work, and shell work. The shell work is joined to the scroll work alternately.

In the centre of each of the scrolls, I place a bouquet or collection of flowers consisting of a rose, Magnolia, and daisies, with their petticoats pointing to the centre.

The centre of the shell work is composed of architectural designs, these scrolls are attached between four radial arms over the centre of which is placed the centre piece in the usual way.

Having thus described my Design, what I claim, and desire to secure by Letters Patent is;

The Pattern for Centre Flower herein set forth.

In witness whereof, I have hereunto set my hand and that this 7th day of August 1878.

Witnesses

G. W. McAdams.
